CATALYST CONVERTER

James M. Jenkins, Philadelphia, Pa., assignor to
 Andale Company, Philadelphia, Pa., a corpora-
 tion of Pennsylvania

Application January 18, 1937, Serial No. 121,043

7 Claims. (Cl. 23—288)

The present invention relates to apparatus for use in the promotion of catalytic reactions and is particularly concerned with certain improvements whereby it is possible to attain greater simplicity and accessibility of structure, efficiency of operation and accuracy of temperature control.

The invention is especially adapted for use in that type of catalyst converter wherein a cooling medium, such as air, is employed for maintaining a liquid bath such as a solution of a suitable salt, metal, or the like, at a substantially constant temperature, the bath, of course, being arranged in heat transfer relationship with the catalyst tubes.

Among the objects of the invention is the provision of a converter of the type described in which ready access may be had to the catalyst tubes as well as to the cooling tubes without disturbance of one or the other and with minimum interference with their associated headers, tube plates, connecting conduits, and the like.

Another object of the invention is to provide a converter of the type described in which the tubes for the cooling medium are disposed in the chamber containing the temperature controlling bath in a direction generally transverse of that in which the catalyst tubes are arranged.

A further object of the invention is to decrease installation and maintenance costs.

How the foregoing together with such other objects as are incident to my invention or which may appear hereinafter are obtained is illustrated in a preferred form in the accompanying drawings, wherein:

Figure 1 is a vertical transverse section through my improved apparatus;

Figure 2 is a partial section on an enlarged scale taken approximately as indicated by the line 2—2 in Figure 1;

Figure 3 is a horizontal section on a scale still larger than that of Figure 2 illustrating the details of construction relating to the cooling tubes; and

Figure 4 is a vertical central section, also on an enlarged scale, through the lower end of one of the catalyst tubes where it passes through the supporting tube plate.

By referring to the drawings it will be seen that my improved apparatus includes the annular liquid bath chamber 5 carried upon the horizontal tube plate 6 which in turn is adapted to rest upon suitable structural foundation work 7. The annular chamber 5 is embraced between the outer cylinder 8 and the inner cylinder 9,

the outer cylinder 8 being seated on the tube plate and the inner cylinder 9 terminating in a plane slightly above the upper face of the tube plate. The bottom of the central opening within the cylinder 9 is closed by means of a plate 10 which provides a connecting passage 11 across the bottom of the device.

The top of the annular liquid bath chamber is closed by the upper tube plate 12 between the periphery of which and the upper portion 10 of the cylinder 8 is provided an annular expansion joint 13. The inner cylinder 9 is welded to the under side of the tube plate 12 as shown.

The catalyst tubes 14 extend vertically through the annular chamber 5 and have their ends suitably connected to the tube plates so as to receive the gas to be treated into their upper ends and to discharge the products of the reaction from their lower ends.

An annular gas inlet header 15 surrounds the upper ends of the catalyst tubes 14 and an opposed header 16 surrounds their lower ends in position to receive the discharged products of the reaction. The gas is delivered to the inlet header through the connection 17 and the products of the reaction are discharged or withdrawn through the connection 18 the direction of flow being indicated by the arrows.

The liquid bath chamber is provided at some suitable location in its circumference with the inlet connection 19 and the outlet connection 20 as well as with an auxiliary drain outlet 21 and a suitable vent 22 in the upper tube plate. The bath may be a liquid salt such as sodium or potassium chloride or a bath of molten metal such as lead but the type of bath has no relation to the present invention and I do not wish to be limited to any particular liquid.

The inlet header 15 is provided at the bottom with a surrounding ring 23 and an inner ring 24 and, at the top, at a plurality of suitably spaced points, with a series of lifting lugs 25. The header 15 is also provided with one or more inspection openings 26 suitably closed by covers 27.

Inside the ring 24 the upper tube plate 12 is formed with a central opening 28 above which is carried a plate 29 formed with a central outlet opening 30 and an annular series of inlet openings 31. The cooling medium, preferably air, comes in through the supply connection 32 and is distributed to the openings 31 by means of an annular header 33. The warm air is discharged through the opening 30 and the outlet connection 35.

34, the direction of circulation being indicated by the arrows.

A cylindrical chamber 35, which is closed at the bottom by a plate 36 located in a plane 5 slightly above the plate 10 in order to provide a horizontal connecting passage 37, is suspended by its upper end 38 from the plates 12 and 29, the end 38 being located to the inside of the annular series of openings 33. It will be seen, therefore, that between the outside of the cylindrical chamber 35 and the inside of the cylinder 9 there is provided an annular chamber 39 which 10 serves as a header chamber for supplying the cooling medium to the cooling tubes in a manner 15 to be described just below. The chamber 35 constitutes an outlet chamber for the warm air, said chamber delivering to the opening 30 and discharge connection 34 as already described.

The cooling medium is carried outwardly from 20 the annular chamber 39 through the liquid bath chamber 5 by means of a plurality of horizontal, radially disposed tubes 40 in the center of each of which is located a return tube section 41, the details of which tubes are shown to best advantage in Figures 2 and 3. The outer ends of the tubes 40 are closed by the plugs 42 and are fitted into positioning sockets 43 carried on the inside of the outer ring 8 of the liquid bath chamber. The inner ends of the tubes 40 are secured in 25 the cylinder 9 in any suitable manner as by means of the welds 44.

The outer ends of the return tube sections 41 are flared slightly and serrated as shown at 45 in Figure 3 in order to provide for ready ingress 35 of the returning warm air which is carried back to the central chamber 35 and there discharged. The inner ends of the tubes 41 are secured in 40 the cylindrical wall of the chamber 35 by means of screw-threaded plugs 46 to which they are welded as at 47.

The tubes 40 with their central return sections 41 are arranged in a series of horizontal planes with the tubes in each plane staggered with respect to the plane immediately above or below 45 as clearly brought out in Figures 1 and 2. The catalyst tubes 14 are disposed between the tubes 40 as most clearly shown in Figure 2 and it will be seen that the cooling tubes are arranged to extend through the liquid bath chamber in a 50 direction which is generally transverse to the direction in which the catalyst tubes extend. Furthermore the catalyst tubes are increased in number from the center outwardly by virtue of the widening spaces about the radially disposed 55 cooling tubes 40. This also is shown to best advantage in Figure 2.

The lower ends of the catalyst tubes 14 are securely fastened in the tube plate 6 as shown in enlarged view in Figure 4, from inspection of 60 which it will be seen that the tube ends are expanded into V-grooves 48 in order to secure a very firm connection between the tubes and the tube plate. This is important because the tubes actually carry the weight of the upper tube 65 sheet 12 and all of the attached parts so as to permit the necessary expansion and contraction, which latter is taken care of by the expansion joint 13 already mentioned. The tubes 14 are, of course, filled to any desired depth with the 70 catalyst 49 which is supported upon the screen 50 located just above the upper surface of the tube plate 6. The screen in turn is carried upon the upper end of a short inner stub tube or bushing 51 under which is placed the supporting 75 pin 52.

A series of thermo couples 53 is provided for the purpose of determining and controlling the temperature of the bath, the control, preferably, being automatic and obtained by means of varying the weight of air which is passed through the 5 cooling tubes.

In operation the chamber 5 is first filled to a suitable depth with the desired liquid bath which is preferably preheated before being introduced through the connection 19. At this time, of 10 course, the outlet 20 and auxiliary drain 21 are closed.

The gases to be treated come in through the connection 17 and are distributed to the catalyst tubes by means of the header 15 in the manner 15 already described and the products of the reaction are collected in the header 16 and discharged through the outlet 18.

As is well known in this art the reaction generates heat and this heat is transferred to the 20 bath and the temperature of the bath is maintained at a substantially constant point by regulating the volume or weight of air which passes inwardly through the connection 32 and from thence to the chamber 39 which communicates 25 with the cooling tubes 40, the air entering the inside of the cooling tubes around the return sections 41 and after traversing the tubes 40 returning through the sections 41 to the central chamber 35 from whence it is discharged through 30 the outlet 34.

The transverse arrangement of the two sets of tubes i. e., the catalyst tubes 14 and the cooling tubes 40 and 41 provides an extremely efficient 35 piece of apparatus and one in which the temperature can be controlled with great accuracy. In addition the structural arrangements are such as to provide for the greatest accessibility to all portions of the apparatus with the least amount of interference with any other portion not involved at the time. For example, the catalyst tubes may be inspected or repaired and the catalyst changed if necessary without in any way disturbing any of the air circulating tubes and connections and vice versa except, of course, 45 that when any tube has to be removed and replaced it may be necessary, with certain types of baths, to drain the chamber 5 while the liquid is hot as otherwise it would become solid and would prevent the removal of the tube. Furthermore, if a tube were removed without draining the bath, the bath, of course, would escape through the opening from which the tube was removed. Many other advantages incident to the 50 structure will be apparent to those skilled in this 55 art.

What I claim is:

1. A catalyst converter, comprising in combination, a liquid bath chamber, vertically extending catalyst tubes passing therethrough, a cooling 60 medium header chamber adjacent a side of said liquid bath chamber, a second cooling-medium header chamber beyond said first header chamber, and horizontal return-flow cooling-medium tubes 65 extending into the liquid bath chamber, the out-flow sections of said cooling-medium tubes communicating with one of said header chambers and the corresponding return-flow sections thereof communicating with the other of said header 70 chambers.

2. A catalyst converter, comprising in combination, a central cooling-medium header chamber, an annular cooling-medium header chamber surrounding said central chamber, an annular 75

liquid bath chamber surrounding said annular cooling-medium chamber, vertical catalyst tubes passing through said liquid bath chamber, and horizontal return-flow cooling-medium tubes extending into the liquid bath chamber, the outflow sections of said horizontal tubes communicating with one of said cooling-medium header chambers and the corresponding return-flow sections thereof communicating with the other of said cooling-medium header chambers.

3. A catalyst converter, comprising in combination, a central cooling-medium header chamber, an annular cooling-medium header chamber surrounding said central chamber, an annular liquid bath chamber surrounding said annular cooling-medium chamber, vertical catalyst tubes in said liquid bath chamber, a tube plate closing each end of the liquid bath chamber, the ends of the catalyst tubes being secured in said tube sheets, an upper and a lower header for circulating the gas to be treated through said catalyst tubes, horizontal return-flow cooling-medium tubes extending into the liquid bath chamber, the outflow sections of said horizontal tubes communicating with one of said cooling-medium header chambers and the corresponding return-flow sections thereof communicating with the other of said cooling-medium header chambers, a cooling-medium supply connection communicating with one of said cooling-medium header chambers, and a cooling-medium outlet connection communicating with the other of said cooling-medium header chambers.

4. A catalyst converter comprising in combination, a central warm air outlet chamber, an annular cold air inlet chamber surrounding said warm air outlet chamber, an annular liquid bath chamber surrounding said cold air inlet chamber, vertical catalyst tubes in said liquid bath chamber, a tube plate closing each end of said liquid bath chamber, the ends of the catalyst tubes being secured in said tube plates, a plurality of horizontal cooling tubes extending from the cold air inlet chamber through the liquid bath chamber, said tubes being closed at their outer ends, and a plurality of warm air return tubes in said cooling tubes, said warm air return tubes extending from a point near the closed ends of the cooling tubes through the annular cold air supply chamber to the central warm air outlet chamber.

5. A catalyst converter comprising in combination, an outer cylinder and an inner cylinder forming an annular liquid bath chamber, a tube sheet closing each end of said chamber, catalyst tubes extending through the chamber and the tube sheets, a gas inlet header communicating with one end of said catalyst tubes, an outlet header communicating with the other end of said catalyst tubes, a cylinder within said inner cylinder cooperating with the latter to form an annular header chamber and itself forming a central header chamber, a plurality of tubes extending from said annular header chamber through said liquid bath chamber in a direction

generally transverse of the catalyst tubes, said transversely extending tubes being closed at their outer ends, a plurality of open-ended tubes within said transverse tubes, said open-ended tubes extending inwardly from a point near the closed ends of the transverse tubes through the annular header chamber to the central header chamber, a cooling-medium supply connection communicating with one of said header chambers, and a cooling-medium outlet connection communicating with the other of said header chambers.

6. A catalyst converter comprising in combination, an outer cylinder and an inner cylinder forming an annular liquid bath chamber, a tube sheet closing each end of said chamber, catalyst tubes extending through the chamber and the tube sheets, a gas inlet header communicating with one end of said catalyst tubes, an outlet header communicating with the other end of said catalyst tubes, a cylinder within said inner cylinder cooperating with the latter to form an annular cooling-medium supply chamber and itself forming a central outlet chamber for the cooling medium, a plurality of cooling tubes extending from said cooling-medium supply chamber through said liquid bath chamber in a direction generally transverse of the catalyst tubes, said cooling tubes being closed at their outer ends, and a plurality of cooling-medium return tube sections within said cooling tubes, said sections extending inwardly through said annular cooling-medium supply chamber and discharging into said cooling-medium outlet chamber.

7. A catalyst converter comprising in combination, a lower or supporting tube plate, an annular liquid bath chamber carried thereon, a plurality of upstanding catalyst tubes in said chamber secured at their lower ends in said supporting plate, an upper tube plate closing the liquid bath chamber, the upper ends of said catalyst tubes being secured therein, an expansion joint between the top of the upper outer wall of the liquid bath chamber and said upper tube plate, a gas supply header for said catalyst tubes carried on the upper face of said upper tube plate, an outlet header for the catalyst tubes below said supporting tube plate, a central warm air outlet chamber carried by said upper plate and forming an annular cold air supply chamber between said liquid bath chamber and said central warm air outlet chamber, a cold air supply connection communicating with said supply chamber also carried on said upper tube plate, a warm air outlet connection on said upper plate, a plurality of horizontal cooling tubes extending from the cold air supply chamber through the liquid bath chamber, said cooling tubes being closed at their outer ends, and a warm air return tube in each cooling tube projecting through the cold air supply chamber and discharging into the warm air outlet chamber.

JAMES M. JENKINS.
